PITCHER

James C. Byrd, Lakeland, Fla.

Application August 13, 1951, Serial No. 16,253

Term of patent 7 years

(Cl. D44—21)

To all whom it may concern:

Be it known that I, James C. Byrd, a citizen of the United States of America, residing at 114 East Palm Drive, Lakeland, in the county of Florida and State of Florida, have invented a new, original, and ornamental Design for Pitcher, of which the following is a specification, reference being had to the accompanying drawing, forming a part thereof, wherein:

Fig. 1 is a front perspective view of a pitcher, showing my new design;

Fig. 2 is a top plan view thereof;

Fig. 3 is a sectional view taken on the line 3—3 of Fig. 2;

Fig. 4 is a sectional view taken on the line 4—4 of Fig. 3; and

Fig. 5 is a rear perspective view thereof.

The dotted lines shown are for illustrative purposes only.

I claim:

The ornamental design for a pitcher, as shown and described.

JAMES C. BYRD.
